UNITED STATES PATENT OFFICE

2,105,181

EGG CARTON

Andrew E. Bueschel, Chicago, Ill., assignor, by
mesne assignments, to Consolidated Carton,
Inc., Chicago, Ill., a corporation of Illinois

Application December 27, 1932, Serial No. 648,973

2 Claims. (Cl. 229—29)

This invention relates to cartons or containers, the construction and arrangement characterizing the present invention being particularly well adapted for use in cartons intended for the packaging and handling of eggs or similar articles.

One object of the present invention is to provide novel cushioning means for eggs or other articles contained within the carton.

Another object of the invention is to provide 10 a novel construction and arrangement whereby certain portions of the carton structure are maintained in desired position, and secured against accidental displacement with respect to other portions of the carton.

Another object of the invention is to provide novel means for supporting a portion of the bottom of the carton.

A still further object of the invention is to provide 20 means whereby the contents of the carton may be readily and conveniently removed.

A still further object of the invention is to improve devices of the character described in sundry details hereinafter referred to and particularly pointed out in the appended claims.

25 One embodiment of the present invention is shown for illustrative purposes in the accompanying drawing, in which

Fig. 1 is a perspective view of a portion of a carton showing the top or cover member broken away at one of its end portions in a manner to more clearly illustrate certain features characterizing the present invention;

Fig. 2 is a fragmentary top plan view of the structure illustrated in Fig. 1 with the top removed, the view being taken substantially as indicated by the line 2—2 of Fig. 3;

Fig. 3 is a fragmentary longitudinal sectional elevation taken substantially as indicated by the line 3—3 of Figs. 2 and 4; and

40 Fig. 4 is an end view of the structure illustrated in Figs. 1, 2 and 3.

The illustrative embodiment of the present invention comprises a carton formed preferably of resilient flexible material such, for example, as 45 cardboard or the like, and having a bottom portion indicated as a whole by the numeral 5 and having side walls 6 and 7, and a top or cover member 8, all formed preferably of a single sheet of material, and having transversely extending partitions 9 connected adjacent their end portions to the side walls 6 and 7, the side walls being shown, in the present instance, as formed integrally with the material from which the bottom 5, side walls 6 and 7 and top or cover member 8 are formed.

The bottom 5, in the present instance, is shown

as provided with longitudinally extending oppositely inclined portions 11 and 12 forming, in effect, a longitudinally extending elevated ridge 13 adjacent the central portion of the bottom 5 and positioned above the outer edge portions thereof.

For supporting the ridge or central portion 13 of the bottom 5 above the outer edge portions thereof, the transverse partitions 9, in the present instance, are provided with notches 14 adjacent 10 their central portions adapted to receive a longitudinal partition 15 in a manner to position the partition 15 laterally of the carton, while the longitudinal partition 15 is provided with a plurality of spaced indentations 16 formed in its lower edge 15 adapted to receive the transverse partitions in a manner to be supported thereby and to position the upper edge of the longitudinal partition 15 against the underside of the top 8 when the latter is in carton closing position, the spacing of the indentations 16 being arranged to position the partitions 9 longitudinally of the carton.

The longitudinal partition 15 is also provided adjacent its extreme lower edge with supporting portions or members 17 adapted to extend downwardly through longitudinally disposed and longitudinally spaced apertures 18 formed in the bottom 5 adjacent the central or ridge portion thereof and extending laterally therefrom at opposite sides of the ridge 13, the supporting member 17 25 extending downwardly to substantially the plane 30 of the outer edges of the bottom portion, and being provided with hook-like portions 19 adapted to be positioned beneath the ridge or central portion 13 of the bottom 5 in a manner to support 35 the central portion of the bottom above the outer edges thereof.

For maintaining the supporting members 17 against longitudinal movement with respect to the apertures 18 when the hook-like portions 19 40 are in bottom supporting position as shown in Fig. 3, and for maintaining the hook-like portions beneath the bottom 5, resilient means shown, in the present instance, as a pair of tabs 21 are formed integrally with the bottom 5 adjacent one 45 end of the apertures 18, the tabs 21 being shown, in the present instance, as extending inwardly from the sides of the apertures 18 at a point beyond the supporting members 17 in a manner to be engageable with an adjacent edge portion of 50 the supporting members 17 when the latter are positioned in the apertures 18 and the portions 19 are beneath the bottom 5 as clearly shown in Fig. 3. It will be apparent from an examination of Fig. 3 that the overall or total width of the

supporting members 17 and hook-like portions 19 is substantially greater than the length of the open portion of the aperture 18, and that when inserting these members and portions 19 in the apertures, the tabs 21 will be bent downwardly, and after the hook-like portions 19 have been positioned beneath the ridge 13 of the bottom 5 as shown in Fig. 3, the tabs 21, owing to the resiliency of the material from which they are formed, will assume their original position with their free ends closely adjacent each other as shown in Fig. 2 in a manner to be engaged by the adjacent edge portions of the supporting members 17 to prevent longitudinal movement of the members 17 in the apertures 18, and thereby prevent displacement of the hook-like portions 19 from beneath the ridge 13 formed in the bottom 5 of the carton.

It will be observed from the foregoing description that the transverse partitions 9 and the longitudinal partition 15 provide compartments for the reception of eggs or other articles and that the oppositely inclined portions 11 and 12 of the bottom 5 provide a resilient support for the eggs in a plane spaced from the plane of the outer edge portions of the bottom on which the carton rests, thereby protecting the contents against damage from below, and by reason of the supporting members 17 extending downwardly to substantially the plane of the outer edges of the bottom 5, and the upper edge of the partition 15 being engageable with the central portion of the top 8, adequate and efficient structure is provided for protection against damage to the contents from the upper side of the carton.

It will be observed also that when the carton is lifted, the hook-like portions 19 serve as an efficient support for the central portion of the bottom 5 to prevent sagging thereof under the weight of the contents, the longitudinal partition 15 on which the portions 19 are formed being suspended from the transverse partitions 9 secured adjacent their ends to the side walls 6 and 7, respectively.

Formed in the upper edges of the transverse partitions 9 are a plurality of finger recesses 22 to facilitate the grasping of an egg, or the like, in removing it from the carton. The partitions 9 are also provided in their lower edge portions with finger recesses 23 through which one's finger may be inserted in a manner to lift an egg, or the like, in an adjacent compartment in a manner to facilitate its removal therefrom.

If desired, the bottom 5 beneath the compart-

ments formed by the transverse partitions 9 and longitudinal partition 15 may be provided with transverse slits 24 to provide yieldable supports 25, which may be bent downwardly to assist in positioning the egg laterally in the compartment 5 and provide additional resiliency in its support.

It will be observed from the foregoing description that the present invention provides novel cushioning means and protection for the contents of the carton by reason of the inclined portions 11 and 12 of the bottom 5, and that novel supporting means are provided for the ridge or central portion 13 of the bottom when the carton is lifted, also that novel means are provided for maintaining certain portions of the carton in desired position and against accidental displacement with respect to other portions thereof, and that novel means are provided for facilitating the removal of the contents from the carton.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to cover by Letters Patent is:

1. A carton having front and rear walls, a bottom member joining said walls, said bottom member having longitudinal slots along its middle portion, a vertical central longitudinal partition positioned above said slots, said partition being provided with downwardly extending hook-like tongues insertable through said slots to hook under the bottom, the bottom wall having a portion located adjacent at least one of said slots on that end opposite the hook, said portion constituting means in the form of two opposing tabs extending transversely to the slot, said means being operative to resist longitudinal movement of the vertical partition in one direction after the tongues have been inserted through the slots.

2. In an arrangement for locking two pieces of sheet material together at an angle to each other, one piece having an elongated slot therein and provided with two opposing tabs formed in said piece to define one end of said slot, and the second piece having a tongue with a lateral notch therein, said tongue at one portion thereof having a width greater than the length of said slot and having a width at said notch slightly less than the length of said slot.

ANDREW E. BUESCHEL.
